UNITED STATES PATENT OFFICE

169,535

SLIPPER OR SIMILAR ARTICLE

John E. Disch, Dolgeville, N. Y., assignor to Daniel Green Company, Dolgeville, N. Y., a corporation of Massachusetts

Application November 18, 1952, Serial No. 22,358

Term of patent 7 years

(Cl. D7—7)

To all whom it may concern:

Be it known that I, John E. Disch, a citizen of the United States of America, residing at the city of Dolgeville, county of Herkimer, and State of New York, have invented a new, original, and ornamental Design for a Slipper or Similar Article, of which the following is a specification, reference being had to the accompanying drawing, forming part thereof.

In the drawing:

Fig. 1 is a perspective view of a slipper, showing my new design;

Fig. 2 is a view of one side of the slipper, and

Fig. 3 is a view of the opposite side of the slipper.

I claim:

The ornamental design for a slipper or similar article, substantially as shown.

JOHN E. DISCH.
